FEEDER AND CATCHER TABLE MECHANISM

Roy J. Leckrone, Mount Lebanon, Pa., assignor
to Continental Roll & Steel Foundry Com-
pany, a corporation of Delaware

Application June 8, 1937, Serial No. 146,998

9 Claims. (Cl. 80—47)

This invention relates to the hot rolling of metal and more particularly to a combined apparatus comprising feeder and catcher tables for use in handling the metal being rolled in a three-high mill.

The feeder table of this invention being adapted for use in connection with a three-high mill is not tiltable but after being moved to position so that its conveyor chains are lined up with the lower pass of the mill, remains stationary. The catcher table is pivotally mounted adjacent its rear end so that after receiving material passing through the lower pass of the mill, it is tilted upwardly about its pivot point and delivers the material to the upper pass. After delivering the material to the upper pass it is moved down to receiving position.

Feeder and catcher tables of the type designed for use in connection with two-high mills are not satisfactory for operation in connection with three-high mills and an object of this invention is to produce an organized apparatus comprising a feeder table, a catcher table and controls therefor suitable for use in connection with a three-high sheet bar or sheet breakdown mill.

Each of the tables of this application embodies hinged side guides and mechanism whereby the operators may readily swing the guides simultaneously toward and from each other to produce a shuffling action for the purpose of lining up the material forming the pack, breakdowns or partly finished sheets as the case may be.

The side guides of the feeder table are so constructed and adjusted that the sheet bars or breakdowns as the case may be on the feeder table may be selectively released, that is, all but the forward sheet bar or breakdown may be held back and the forward sheet bar or breakdown, no matter where the same is located carried on by the conveyor to the lower roll pass.

The feeder table also includes a front stop under the control of the operator by means of which the sheet bars, breakdowns or sheets as the case may be may be matched.

Both the feeder and catcher tables with their operating motors are self contained, that is, the feeder table is mounted upon a base which carries its operating motor and reducing gear set so that the table and its operating motor and gear set can be moved as a unit to and from position. This is also true of the catcher table and its operating motor.

The forward end of the supporting base for each table is provided with leveling jacks for lining up the top of the forward ends of the con-

veyor chains of the tables with the lower pass of the mill.

Rack and gear devices are utilized for supporting the rear end of the supporting bases and by means of these devices, the tables and their operating motors and reducing gear sets may be moved as complete units toward and from the mill, for the purpose of properly positioning the tables with relation to the mill and also for the purpose of moving the same away from the mill when roll changes are to be made. The catcher table is raised and lowered about its pivot point by means of a reducer set having crank arms connected to the main frame of the catcher table. The reducer set and its motor are supplemented by a spring motor utilizing nested compression springs. This spring motor assists the reducer set and its motor in raising the table about its pivot point and tends to cushion the downward movements of the table.

The catcher table is provided with a middle stop which can be moved to different positions longitudinally of the table in order to take care of various lengths of material being rolled. The catcher table is also provided with a back stop under the control of the operator and with pinch rolls at the rear end of the table which are also under the control of the operator and which feed the finished sheets to a piler.

The operators' chairs, one for the feeder table and one for the catcher table, also form part of the organized apparatus and these chairs are located adjacent the rear end of each table with both operators facing the mill. While these chairs are bolted to the table or foundations and are not carried by the table supports the operating shafts extending from the chairs to the table are made extensible and provided with universal joints so that the tables may be adjusted toward and from the mill without disconnecting the operating levers which are mounted at the chairs.

In the drawings:
Figures 1 and 2 taken together (Fig. 2 being a continuation of Fig. 1) illustrate in side elevation a feeder table embodying this invention;

Feeder table

The frame of the feeder table is preferably fabricated from rolled shapes and plates such as channels 30 and 31 which constitute the frame side members, channel 32 which constitutes the back cross member and plate 33 which forms the flooring or bed for the frame. The frame is mounted on a base plate 34 which in turn is supported by suitable channels and I-beams 35 which are collectively designated by the numeral 35. Pedestals 36 support the rear of the table frame and pedestals 37 support the forward part of the frame. A chain conveyor drive shaft 38 extends across the frame at its rear and is journaled in suitable bearings carried in the top portion of pedestals 36. Shaft 38 carries suitably spaced chain sprockets 39 and 40 and the shaft is coupled to the low speed shaft of a worm reduction gear set 41 which is mounted on an extension 42 of the base. The high speed shaft of this worm reduction gear set is connected to a reversible motor 43 which is also mounted on extension 42 of the base. A shaft 44 journaled in the forward end of the table frame carries chain wheels 45 and 46. Conveyor chains 41 are trained over sprockets 39 and 40 and wheels 45 and 46 and these chains are kept taut by means of spring actuated chain tighteners 48 of well known construction. Wear plates 49—49 are

secured to table plate 33 below the upper runs of chains 47 and the lower runs of the chains are supported on idler rollers 50 and 51. The forward portion of the table is provided with upstanding chain guides 52 on each side of the wear plates 49 while the rear of the frame is provided with upstanding chain guides 53 located on opposite sides of the wear plates 49.

A sectional water cooled roller 54 is supported by brackets 55 which are secured to and extend forwardly of the forward end of frame side channels 30 and 31. The top of this roller is in line with the top of conveyor chains 47—47 and serves as a support for the material passing from the conveyor to the lower roll pass.

This roller, as said, is sectional and is made up of a number (four) of tube-like members, preferably made from some heat resisting alloy. These members are mounted on a stationary shaft and fabricated bearings are interposed between these members and said shaft. The shaft is hollow and is supplied with water which passes out of the same through radial holes formed therein.

Each of the outer channels 35 is provided with a relatively short longitudinally grooved contact plate 56. Screw jacks 57 (there being one for each side) secured to the foundation and having their upper surfaces lying within the grooves of said contact plates support the forward portion of the feeder table. By means of these jacks the forward end of the table may be raised and lowered slightly so as to line up roller 54 with the lower pass of the mill. a indicates the upper roll of the mill, b the middle roll and c the lower roll.

The rear of the feeder table is supported by two rack and spur gear devices 58 shown more or less in detail in Fig. 22.

A wrench in the form of a long lever for operating the spur and rack mechanisms as well as the jacks is indicated by dotted lines in a number of the figures of the drawings and it will be understood that it is only used for racking the tables to and from position and for raising and lowering the forward ends thereof.

Racking mechanisms

The base member, beside the side channels 35 and base plate 34 has a bottom plate 59 and 60 longitudinally extending stiffening members in the form of I-beams 60. Two rack mechanisms for racking the feeder table toward and from the mill are used for the feeder table. The racks are secured to the under side of the base adjacent its rear end, and in line with pedestals 36. The spur wheel portion of each of these devices is bolted to the foundation. This portion comprises a shaft 61 which extends from one racking mechanism to the other at right angles to the longitudinal axis of the feeder table and is journaled in bearings 62 and 63 within brackets 64 and 65 which are secured to the foundation by bolts 66—66 (see Fig. 22). Cap portion 67 of one of the brackets 64 is split as shown in Figs. 1 and 22 and a clamp bolt 68 is provided for clamping shaft 61 against rotation. Shaft 61 inside of each set of brackets and adjacent thereto is provided with a spur wheel 69 and these are keyed to the shaft. The hub of each spur wheel is provided with a hardened steel ring 70 which is preferably shrunk thereon. A relatively short rack is provided for each spur gear. These racks are numbered 71—71 and are secured to the under side of the base member in line 75

with the spur gears. Each rack member is provided with a hardened steel bearing plate 72 which parallels the rack teeth and bears on one of the wear rings 78. The weight of the rear 5 of the table is therefore taken by shaft 61 through rings 78 and plates 72. From this construction it will be seen that the racks and spur gears bear no weight and the racking of the table toward and from the mill is their sole function.

10 One end of shaft 61 is squared as shown at 73 to receive the actuating wrench.

Shuffling mechanism

15 The side guides are shown in plan at 74—74, Figs. 3 and 4, one in side elevation in Fig. 1 and they are shown in transverse section in Fig. 11. Each of the guides at its rear end is flared outwardly as shown at 75 to facilitate entrance of sheet bars therebetween. Each guide from point 20 76 to a point 77 adjacent its forward end is flared outwardly as shown in Figs. 3 and 4. A stiffener rib 78 welded to the back of each side guide 74 extends throughout the major portion of its length. Each of the side guides has a wear plate 25 79 of some suitable heat resisting metal secured to its inner face. Each guide is carried upon a pair of swinging levers, those for one of the guides being numbered 80 and those for the other being numbered 81. The levers of each pair 30 are spaced apart longitudinally of the table and between each side guide and each lever 80 a tubular sheet metal spacer 82 is interposed. Bolts 83 extend through each spacer and side 35 guide and secure the guides to the levers. Each lever is preferably formed in two parts (Figs. 11, 14 and 15) bolted together at 84. The lower part of each lever is forked as clearly shown in Fig. 15 and the parts are pivotally mounted on a shaft 85 by means of ball bearings 86. Shaft 40 85 is secured within the depending portion 87 of a bearing block 88 which surrounds a more or less rectangular bar 89. The lower forked portion of each lever is bent at an angle to the remainder of the lever as shown in Figs. 11 and 14 and stiffening ribs 90 are provided for the fork portions. Bar 89 is carried in support brackets 45 91—91 and is bolted thereto at 92—92. These brackets depend from channel side members 30 and 31 and are bolted to said channel members at 93—93 and 94—94.

The top surface of bar 89 adjacent each end thereof has rack teeth 95 cut therein. The top of levers 80 and 81 extend outwardly as shown at 96 and the extreme outer end 97 of each such extension is bent downwardly at an angle and is pierced to loosely receive a rod 98. This rod is threaded at its upper end and is provided with a hook at its lower end as shown in Fig. 11. A coil spring 99 has its upper end engaged by 50 said hook and its lower end hooked into a screw eye 100 which is threaded into an extension 101 of bearing block 88. The tension of spring 99 is adjusted by means of a wing nut 102 which bears against a bearing washer 103 which loosely surrounds rod 98 and rests against the upper surface of the downturned part 97 of extension 98 of each of the levers. Spring 99 of lever 80 tends to move said lever toward the left of Fig. 11, while spring 99 of lever 81 tends to move said lever to the right of Fig. 11. Stop screws 104 which are threaded through flanges 105 of bearing blocks 88 form adjustable stops for limiting the outward movement of levers 80 and 81. These screws are adjusted so that the levers and 55 the side guides 74 carried thereby may be easily

oscillated in and out to obtain the desired shuffling action.

Mechanism for oscillating the side guides

A shaft 106 journaled for oscillation in suitable bearings carried by brackets secured to and depending from plate 33 in line with levers 80 and 81 is provided with a pair of oppositely extending crank arms 107 and 108. One end of shaft 106 carries a mitre gear 109 which meshes with 10 a suitable gear 110 carried on a shaft 111 which extends outwardly through an opening in the web of channel side member 30 and which is journaled within suitable bearings 112 and 113 respectively carried by said channel 30 and 15 plate 33.

A bar 114 preferably bent as shown in Fig. 11 and having its inner end provided with a bearing portion 115 which surrounds the pin of 20 crank 107 has its outer end drilled to provide a series of aligned circular holes 116. A pin 117 carried by a pad 118 secured to lever 80 has a hole drilled therethrough from top to bottom to receive a tapered pin 119. Pin 117 projects through one of the series of holes 116 and tapered pin 119 locks bar 114 in position on pin 117. A bar 120 bent in the reverse direction from bar 114 as will appear from Fig. 11, has its end bearing 121 surrounding the pin of crank 108. This outer end is provided with a series 25 of holes 122 and this bar is locked in position on pin 123 by a tapered pin 124.

In order to adjust the position of levers 80 and 81 to accommodate the shuffling mechanism to material of different widths, the bearing blocks 30 35 88 which carry pins 85 upon which the levers are mounted may be moved toward and from one another. This movement or adjustment is accomplished by unlocking the bearing blocks from bar 89, moving them manually to the desired 40 positions and then locking them in such positions. The locking mechanism for each bearing block comprises a shaft 125 journaled in bearings formed in extensions 126 and 127 of bearing block 88. One end of the shaft carries an 45 operating lever 128 and the other end a locking cam 129 which, when lever 128 is turned to horizontal position as shown in Figs. 11, 13 and 15, moves to position between two of the rack teeth 50 95.

These mechanisms are identical for both levers 80 and 81 and one description will suffice for both.

The adjustment of the parts as shown in Fig. 55 11 is suitable for handling the narrowest material and with this adjustment the side guide 74—74 or that portion thereof between out-flared ends 75 and flared side portions 76 is substantially perpendicular when at rest. When wider material is to be rolled, the bearing blocks 60 65 are unlocked and moved the desired distance apart. Bars 114 and 120 are disconnected from pins 117 and 123 and said pins are entered in the proper holes of series 116 and 122 to correspond with the new position of the bearing blocks. 65

The outer end of shaft 111 by means of universal joints 130 and 131, shafts 132 and 133 and a tubular extensible coupling member 134 is connected to a stub shaft 135 which carries an operating lever 136 at the operator's chair 137. 70 From this construction it will be apparent that shaft 106 may be oscillated by swinging operating lever 136 and thus cause hinged side guides 74—74 to approach and recede from one another thus accomplishing the shuffling action of break- 75

downs or partially finished sheets as the case may be while the same are supported on the chain conveyor.

Feeder table back stop

The feeder table, just behind the flared entrance ends of side guides 14 is provided with a back stop which when in raised or operative position, stops the advance of sheet bars which are being carried forward by the chain conveyor. This back stop is shown in detail in Fig. 12 and comprises two squared members or fingers 138. These as shown in said figure are spaced apart and when in operative position, project above the top surface of the conveyor chains. Members 138 are pinned to a shaft 139 which is mounted for oscillation within bearing members 140-140 secured to and depending from plate 33. One end of this shaft is provided with a crank arm 141 and this arm by means of a link 142 is connected to crank arm 143, the hub 144 of which is pinned to a shaft 145. Shaft 145 extends across the table and is journaled in bearing blocks 146-146 which are bolted to the webs of channel side members 30 and 31. This construction is such that when members or fingers 138 are raised to operative position as shown in Figs. 1 and 12, link 142 and crank arm 143 which form a toggle are lined up, and thus in effect form a lock for locking members 138 in raised position and for preventing rotation of shaft 145 by the sheet bars as they collide with the stop members.

One end of shaft 145 by means of suitable universal joints 147 and 148, shaft sections 149 and 150 and a tubular extensible coupling member 151 is connected to a stub shaft 152 at the feeder table chair 137. This stub shaft carries an operating lever 153 and full movement of the operating lever to the right (Fig. 23) will move stop fingers 138 to the position shown in Figs. 1 and 12; full movement to the left position shown in Fig. 23 will move the fingers to the position shown in Fig. 3.

Feeder table front stop

The feeder table adjacent its forward end, as shown in Fig. 1, is provided with a stop which is used in matching breakdowns or sheets, as the case may be, prior to their entrance into the lower pass of the mill. This stop is shown in front elevation in Fig. 16 and in perspective in Fig. 17. The stop comprises two squared pins or fingers 153a-153a which when in elevated position as shown in Figs. 2, 16 and 17, extend a distance above the tops of the conveyor chains. A stop plate 154 is bolted to the rear faces of said fingers and serves as the primary stop member.

Each of the fingers 153a-153a is bolted to the top portion 155 of a crank arm 156. The crank arms and their hubs thus form two bell crank levers.

Each of the hub portions is provided with a squared hole extending therethrough and within which snugly fits one of the squared ends 157 of a shaft 158.

The forward end of plate 33 is cut away to receive the back stop assembly as shown in Fig. 17. Shaft 158 is journaled in two hollow cylindrical bearing members 159 and 160 and each of these bearing members is provided with a plate-like extension 161 which is bolted to the underside of plate 33. Anti-friction bushings are inserted between the shaft 158 and the inner bore of bearing members 159 and 160.

A bearing bracket member 162 bolted to the

inner face of the channel 30 is provided with a cylindrical bore 163 and a similar bearing bracket member 164 is provided with a cylindrical bore 165. These bores are shown by dotted lines in Fig. 16. A square shaft 166, provided with cylindrical ends 167-167 has such ends journaled within said bores 163 and 165. Shaft 166 carries two crank arms 168 and 169 and each of these is provided with a hub portion 170 having a squared through hole which snugly fits the squared portion of shaft 166 and lies immediately adjacent one of the bearing bracket members. Each of these crank arms is connected to the outer end of crank arms 156 by a pair of links 171. Hub 170 of crank arm 168 is provided with another crank arm 172 which with said hub and arm 168 forms a bell crank lever. The outer end of crank arm 172 is connected to the bifurcated end 173 of a shaft or rod 174 which extends longitudinally of the table. The opposite end of shaft or rod 174 is bifurcated and is connected to a crank 175 which is keyed to a shaft 176. Shaft 176 extends across the table and is journaled in suitable bearings secured to channels 30 and 31. One end of shaft 176 by means of universal joints 177 and 178 and shaft sections 179 and 180 and a tubular slip coupling 181 is connected to a stub shaft 182 at the operator's chair. Shaft 180 is provided with an operating handle 183 and by means of this handle the front stop 30 may be raised and lowered as desired.

The catcher table

The catcher table frame is a substantial duplicate of the frame of the feeder table, so also is the base upon which the frame is mounted. The catcher table is pivotally mounted at its rear end on the shaft which carries the driving sprockets for the conveyor chains. The motor and worm reduction set for raising and lowering the table about said shaft are located directly beneath the table and because of this, the pit within which the table is positioned must be deeper than that within which the feeder table is positioned. The pedestals within which the upper portion of the pivot shaft is journaled are mounted on supports carried by the table base.

The motor and reduction gear for driving the conveyor chains are mounted on an extension of the base as shown in Fig. 10 and as with the feeder table, the forward end of the catcher table is mounted on jacks which are identical with the jacks employed in connection with the feeder table. The rear of the base is mounted on racking devices identical with those employed in connection with the feeder table.

The forward end portions of the channels forming the sides of the table frame are reduced in height (Fig. 5) in the same manner as the forward ends of the side channels of the feeder table. This reduction in height of the side channels is for the purpose of permitting the tables to be moved close to the rolls of the mill.

The driving sprockets for the conveyor chains are numbered 184-184 and are keyed to shaft 185 which forms the pivotal mounting for the rear end of the catcher table. This shaft is journaled in bearings in the upper portions 186 of pedestals 187. One of the supports referred to for the pedestals is numbered 188 and the table base is numbered 189.

190 is the reversible motor for driving the conveyor chains through a gear reducing set 191. Motor 192 for raising and lowering the table as shown in Figs. 5 and 7 is located directly beneath

75

Back stop

the longitudinal center of the table. Its shaft is coupled to the high speed shaft of a worm reducer set 193. The low speed shaft 194 of the reducer set carries two crank arms 195 (one being shown in Fig. 5). Motor 192 through reducer 193 is adapted to raise and lower the catcher table about its pivotal point. Each of the side channel members of the frame, in line with reducer 193, carries a bearing bracket 196 and each of these brackets carries a pin 197. Connecting rods 198 connect these pins with pins 199 of cranks 195.

The operation of motor 192 is controlled by a foot switch 202 at chair 201.

15

Tilting motor assisting mechanism

In order to assist motor 192 in tilting the table about its pivotal mounting and to cushion the 20 downward movements thereof I employ a mechanism comprising two spring devices 202—202. These are positioned beneath the channel side members of the frame between motor 192 and the gear reducer 193. Each of these comprises 25 a tubular barrel 203 (Figs. 20 and 21), which extends through an opening in floor plate 204 of base 189 and is supported in place by means of a bracket 205 secured to the top of said plate.

Barrel 203 is provided with a telescopically arranged bottom member 206 which is held in place by rods 207. These rods project through ears 208—208 which are welded to bracket member 205 as shown at 209. The telescopically arranged bottom member 206 is also provided with welded 35 ears 210—210 through which rods 207 pass. The upper ends of rods 207 are threaded to receive adjustment nuts 211 and the lower ends of such rods are provided with heads 212. These rods while they permit upward movement of bottom member 206, limit its downward movement. 40 The bottom of member 206 is provided with drain holes 213. Two sets of nested coil springs as shown in Fig. 21 are positioned within barrel 203 and the sets are separated by a separator 214 having upper and lower annular flanges respectively numbered 215 and 216. This separator has a loose fit in the inner bore of barrel 203 and is provided with a centrally arranged vent opening 217. The flanges 215 and 216 hold the ends of 45 the outer springs out of contact with the walls of the barrel. An annular top member 218 having a downwardly extending annular flange 219 rests on the top of the upper set of springs and said flange prevents the top ends of the outer spring 50 of the upper set from contacting with the inner wall of barrel 203.

A plunger 220 rests on the top of annular member 218 and a plunger rod 221 pivotally connected to the plunger by means of pin 222 has its 55 upper end formed in the nature of an eye 223. This eye is pivotally secured within a bracket member 224 by means of a pin 225. The bracket member is bolted to one of the channel side members of the table frame as shown in Fig. 20. A 60 tubular cover member 226 the inner diameter of which is materially greater than the outer diameter of barrel 203 (Fig. 20) is secured to plunger rod 221 by means of a two part head member 227. This tubular cover member prevents scale and 65 other extraneous matter from entering barrel 203. Barrel 203 is provided with one or more openings 228 so that oil may be poured in on the springs and sliding spacers. A magnetic brake 229 is operatively connected to the shaft of motor 192.

Middle stop

15

The catcher table is provided with a middle stop which is movable to different positions longitudinally of the table to accommodate the rolling of material of different lengths.

This middle stop is shown in detail in Figs. 18 20 and 19. Two strips 237 of plate material each provided with a series of aligned holes 238 are secured in place just inside of the conveyor 25 chains and extend throughout that portion of the table within which it is desired to secure the middle stop.

The middle stop comprises stop plate 239 which is carried by two curved and spaced arms 240—240 secured to a shaft 241. The distance between the outside faces of arms 240 is slightly less than the distance between the inner edges of strips 237. Shaft 241 extends in opposite directions beyond the outer side faces of arms 240 and this bar is permitted to turn and is held in place by inverted U bolts or pins 242.

The assembly made up of shaft 241, bracket arms 240 and stop member 239 may be adjusted to the desired position between the ends of strips 237 and anchored in place by placing U bolts or pins 242 over the extended ends of shaft 241. 40 The legs of these bolts or pins extend down through aligned pairs of openings 238 and thus hold the middle stop in the position desired.

The lower faces of bracket arms 240 rest upon the upper faces 243 of a pair of angles. The 45 downwardly extending portions 244 of these angles are carried on the upper arms 245 of a pair of bell crank levers which are mounted on spaced shafts 246 which extend across the table beneath the upper deck thereof and are journaled 50 within suitable bearings carried by the channel side members of the frame. The lower arms 247 of each pair of bell crank levers are connected to a reciprocating actuating rod 248. These rods connect with the lower ends of levers 249 which 55 are carried by a rod 250 which extends across the table and is journaled in suitable bearings carried by the channel side members of the frame. Shaft 250 by means of universal joints 251 and 252, shaft sections 253 and 254 and 60 tubular telescoping coupling 255 connects with operating lever 256 at catcher table chair 201. When lever 256 is swung to the right (Fig. 25) shaft 248 will be moved to the left (Figs. 18 and 19) and the angles which support bracket arms 65 240 will be lowered. This will allow stop member 239 to drop below the top surface of the conveyor chains and out of the path of the material traversing the table.

The shuffling mechanism for the catcher table 70 is identical with that of the feeder table and shaft 257 which is the operating shaft for the shuffling mechanism is connected with stub shaft 258 at catcher table chair 201. This shaft carries an operating lever 259 and is connected to 75

operating shaft 257 by means of universal joints 260 and 261, shaft sections 262 and 263 and an extensible coupling 264. The dotted line positions of lever 259 shown in Figure 25 indicate the lever's extreme positions in moving the side guards 265 of the shuffling mechanism toward and from the material on the chain conveyor.

A pair of feed rolls 266 are positioned at the rear end of the catcher table for feeding the finished sheets to the receiving table or other support. The shafts 267 and 268 of said rolls are journaled in suitable bearings mounted for vertical sliding movement within windows 269 in bracket members 270. These brackets are secured 10 to the rear end of the table frame and the lower roll is driven by a motor 271 through drive chain 272.

The pinch rolls are held in contact by means of springs 273 (one over each of the bearings 20 of the upper roll) and the tension of these springs is adjusted by means of screws 274.

Means are provided for lining up the ends of the sheets delivered by the pinch rolls and this means comprises an aligning member 275 which 25 is mounted for oscillation on a shaft 276. This shaft is carried in spaced bracket members 277 secured to support member 188. The aligning member is operated by a pivotally mounted air cylinder 278 the plunger rod 279 of which is 30 connected to a pin 280 carried by the aligning member.

The operation of the pinch rolls and the aligner are under the control of the operator at chair 201.

35

Chairs

Chair 137 is provided with a foot switch 281 for controlling the operation of the chain conveyor of the feeder table. This chair will also be provided with a furnace door operating switch. 40 As shown in Fig. 10, chair 137 for the feeder table operator is in line with the shaft which carries the driving sprockets for the feeder table conveyor.

Chair 201 for the catcher table operator is in 45 line with the shaft which carries the sprockets for the conveyor of the catcher table. This table is provided with a foot switch 282 for controlling the operation of the table lifting motor 192 and motor 190 which operates the chain conveyor 50 for the catcher table. Chair 201 will also be provided with a starter button for the pinch rolls. The chairs face the mill and are raised a slight distance above the mill floor so that the operators can at all times see just what is going 55 on and have complete control of all operations.

A rotatable shaft 283 driven by gearing (not shown) from shaft 194 of reducer 193 operates a limit switch 284. This switch will be connected up to the current supply for motor 192 and with 60 magnetic brake 229 (Fig. 6) so that the current supply for motor 192 will be cut off when the table reaches the limit of its upper position as shown by dotted lines in Fig. 5, as well as when it reaches the limit of its down position. When the current supply is cut off, rotation of motor 192 will 65 be stopped by magnetic brake 229.

As shown in Figs. 3 and 11, shims 285 are placed between spacers 82 and side guides 74 at the rear end of the feeder table so that the 70 side guides at this position are brought slightly closer together for about two to two and one-half feet than throughout the remainder of their length. This permits the operator at the feeder table chair 137 to pinch the back sheet bars on 75 the chain conveyor and hold them while per-

mitting the front sheet bar, no matter where the same is located, to be conveyed to the lower pass of the mill. In this way, the feeder table operator can time the delivery of sheet bars to the mill. It is only at the rear end of the 5 feeder table that the side guides are shimmed.

Front stop 154 of the feeder table is used for matching the breakdowns and partially finished sheets, thus the breakdowns and partially finished sheets issue from the upper pass of the 10 mill, pass over this stop and fall onto the chain conveyor of the feeder table. When the conveyor is reversed, the conveyor carries the material up against the stop and in this way matching of the same takes place.

Middle stop 239 of the catcher table will be moved to the proper position to take care of the particular sheet bars being rolled. If narrow bars are being rolled, this stop will be adjusted toward the forward end of the catcher table. 20 If wide bars are being rolled, then it will be adjusted further from the front end of the table.

The front stop of the catcher table is maintained in raised position until each rolling operation has been completed. When the sheets are 25 passed through the last pass, this stop is lowered, thus allowing the sheets to be carried into the bite of the pinch rolls.

The tension of the nested coiled springs in barrel 203 may be adjusted by means of nuts 211. 30 The telescoping bottom member 206 permits the springs to be compressed as they become weakened without changing the position of annular contact member 218 against which plunger 220 bears.

Instead of having the operator's chairs arranged so that the operators face the mill, it will be understood that the chairs may be arranged so that the operators face the tables, or the chairs may be arranged diagonally. Either 40 arrangement will allow the operators to watch the entire rolling procedure. When the chairs are arranged as above suggested, it of course will be necessary to modify the connections between the operating levers and the operating shafts.

Having thus described by invention, what I 45 claim as new and desire to secure by Letters Patent is:

1. In combination with a rolling mill stand, feeder and catcher tables located on opposite 50 sides of said stand, spaced chain conveyors for each table, pivoted side guides for each table so mounted as to be movable toward and from said conveyor, swinging stops for each table, an operator's chair located on the mill floor adjacent 55 the rear of each table and at one side thereof, levers at said chair for operating said stops and said side guides and means operatively connecting said levers to said stops and side guides; said levers being so arranged that the operator, without leaving his chair may operate said stops and side guides.

2. The combination in a catcher table having a chain conveyor, of a pivotally mounted stop movable to different positions lengthwise of the 65 table, a support for said stop extending throughout that portion of the table within which said stop is to be moved and means for raising and lowering said support.

3. The combination with a material handling 70 table for use in connection with a rolling mill stand, of a chain conveyor, shuffling means for aligning the material carried by said conveyor, front and back stops for said table, a base upon which said table and its operating motor and 75

- gear set are mounted, jacks for supporting the forward end of said base, racking means for supporting the rear end of said base, whereby the table, said motor and said gear set may be moved as a unit, an operator's chair located on the mill floor adjacent the rear of said table and at one side thereof, operating levers at said chair for operating said stops and said shuffling device and extensible connections between said levers and said stops and shuffling device.
4. The combination with the chain conveyor of a material handling table for rolling mills, of side guides on opposite sides of said conveyor, pivotally mounted supports for said guides; the pivot points of said supports being located below said conveyor, notched means extending outwardly on each side of said table a distance above said pivot points, supports mounted on said means and which carry said pivot points, means for locking said supports in different positions along said means to vary the normal distance between said side guides and means for simultaneously operating said side guides.
5. The combination with the chain conveyor of a material handling table for rolling mills, of side guides on opposite sides of said conveyor, pivotally mounted supports for said side guides having their pivot points located below said conveyor, brackets carrying said pivotal mountings and which are adjustable to different positions laterally of said table, stops on said brackets for limiting the outward swinging movement of said side guide supports, springs for yieldingly holding said side guide supports in contact with said stops and means for simultaneously swinging said supports either toward or from said stops.
6. In a combined support and racking device for use in supporting one end of a mechanical table, a rack extending longitudinally beneath the table, a wear plate paralleling said rack, a shaft extending transversely of the table below said rack and wear plate, supports within which
- said shaft is journaled, a gear carried by said shaft and meshing with said rack and a wear ring carried by said shaft and upon which said wear plate bears.
7. In a combined support and racking device for use in supporting one end of a mechanical table, a rack extending longitudinally beneath the table, a wear plate paralleling said rack, a shaft extending transversely of the table below said rack and wear plate, supports within which said shaft is journaled, a gear carried by said shaft and meshing with said rack, a wear ring carried by said shaft and upon which said wear plate bears, and means for locking said shaft against movement.
8. In a combined support and racking means for use in supporting one end of a mechanical table, spaced racks extending longitudinally below the table, wear plates paralleling said racks, a shaft extending transversely of the table beneath said racks and wear plates, supports within which said shaft is journaled, gears carried by said shaft and meshing with said racks, wear rings carried by said shaft and upon which said wear plates rest and means for locking said shaft against rotation.
9. The combination with the frame side members and platform of a material handling table, of a chain conveyor comprising separated endless chains having their upper flights mounted for movement above said platform, and a shuffling mechanism comprising spaced side guides located outside of the upper runs of said conveyor chains and extending above the same, support arms for said side guides hinged to support members located below the table side members and which are movable to different positions laterally of the table, means for locking said support members in adjusted position and means for simultaneously rocking said support arms to move said side guides toward or from said conveyor.

ROY J. LECKRONE.
